CLAIM

The ornamental design for a winter weather footwear, as shown and described.

DESCRIPTION

FIG. 1 is a front perspective view of a winter weather footwear, showing our new design;

FIG. 2 is a rear perspective view thereof;

FIG. 3 is a right side elevational view thereof;

FIG. 4 is a left side elevational view thereof; and,

FIG. 5 is a bottom plan view thereof.

The broken line showing of the stabilizer in FIGS. 1-4 is for illustrative purposes only and forms no part of the claimed design.
